Primary Examiner — Cynthia Ramirez(74) *Attorney, Agent, or Firm* — Frost Brown Todd LLC(57) **CLAIM**

The ornamental design for a superstructure for receiving rotatable lift arms in an automotive vehicle lift, as shown and described.

DESCRIPTION

FIG. 1 is a top perspective view of a superstructure for receiving rotatable lift arms in an automotive vehicle lift, showing our new design;

FIG. 2 is a bottom perspective view thereof;

FIG. 3 is a rear perspective view thereof;

FIG. 4 is a front elevational view thereof;

FIG. 5 is a back elevational view thereof;

FIG. 6 is a left side elevational view thereof, the right side being a mirror image thereof;

FIG. 7 is a top plan view thereof; and,

FIG. 8 is a bottom plan view thereof.

The lower plate structures shown in broken lines are unclaimed environment, and form no part of the claimed design.
